UNITED STATES PATENT OFFICE.

JOHN MINOT FISKE, OF NEW YORK, N. Y.

DESIGN FOR A STALL-FLOOR SUPPORT.

SPECIFICATION forming part of Design No. 26,443, dated December 22, 1896.

Application filed November 7, 1896. Serial No. 611,410. Term of patent 14 years.

To all whom it may concern:

Be it known that I, JOHN MINOT FISKE, a citizen of the United States, residing at New York, in the county and State of New York, have invented and produced a new and original Design for Stall-Floor Supports, of which the following is a specification, reference being had to the accompanying drawings, forming a part thereof.

10 My present invention relates to a novel design for stall-floor supports, which will be hereinafter more fully set forth.

In the annexed drawings, Figure 1 is a perspective view of the support; Fig. 2, a longitudinal sectional view, and Fig. 3 an end view.

15 A indicates the base, rectangular in its general outlines, provided at its upper end with an upstanding and overhanging flange B. A series of channels or depressions C extend 20 from the head to the lower end of the base, gradually deepening from the upper end thereof. A pin or stud D is formed near the end of each channel. E denotes a series of gutters or ways also extending from the head of the base to the foot intermediate the channels C, the division between these parts being formed by the upstanding walls α , having the shoulders or stepped portions b . These gutters also become deeper as they approach the lower end of the base. The outer walls of 30 the outer gutters E are not provided with stepped portions, as are the other walls α intermediate thereof. A narrow beaded flange or lip F extends around both sides and the head of the base.

35 Having thus described my invention, what I claim is—

The design for stall-floor supports substantially as shown and described.

In witness whereof I hereunto set my hand 40 in the presence of two witnesses.

JOHN MINOT FISKE.
